COMB CLEANER

Patty Shepherd Keyser, Boise, Idaho

Application May 4, 1939, Serial No. 271,798

1 Claim. (Cl. 132—29)

This invention relates to comb cleaners, and has for one of its objects the production of a simple and efficient means for facilitating the clamping and holding of comb-cleaning threads in a firm and set position with respect to the supporting element.

A further object of this invention is the production of a simple and efficient gripping element for firmly holding the comb-cleaning threads against slipping in a manner whereby the threads are prevented from becoming accidentally detached from the supporting medium.

Further objects and advantages of the present invention will be apparent throughout the following specification and claim.

In the drawing:

Figure 1 is a front elevational view of the device, certain parts being shown in section;

Figure 2 is a side elevational view;

Figure 3 is an enlarged vertical sectional view taken on line 3—3 of Figure 1;

Figure 4 is a front elevational view of a modified form of the invention, certain parts being shown in section;

Figure 5 is a side elevational view of the device shown in Figure 4;

Figure 6 is an enlarged vertical sectional view taken on line 6—6 of Figure 4; and

Figure 7 is a detail perspective view of a portion of the thread-clamping head.

By referring to the drawing, it will be seen that 10 designates the hanger member which is provided with a transversely extending supporting bar 11 at the bottom thereof, over which the comb-cleaning threads 12 are adapted to be folded or overlapped in the manner shown in detail in Figure 3. A clamping member 13 which may be formed of suitable material and spring metal if desired, is adapted to fit over the folded portion 14 of the threads 12, in the manner shown in Figure 3, the clamping member 13 having gripping edges 15 which grip the threads 12 as they pass from under the clamping member 13. This clamping member 13 is preferably of an elongated structure of the length of the bar 11, and is adapted to firmly grip the entire transverse area of the comb-cleaning threads or cords 12 at the point where these cords 12 overlie or are folded over the bar 11. This clamping member 13 is adapted to firmly clamp the threads against the bar 11 and the lower edges 15 are also adapted to firmly grip the threads or cords 12 so as to hold these cords against longitudinal slipping and prevent the cords from being pulled out of engagement with the clamping head as the teeth

of a comb are passed between the threads or cords 12 in the conventional manner. The ends of the cords, because of this clamping member 13, will be firmly held at uniform lengths in a manner as shown in Figure 2, and furthermore they 5 will be held against longitudinal pull and dislocation from the head through the medium of this clamping member 13, which clamping member 13 is preferably permanently fixed in position.

It should be understood that in the form shown 10 in Figures 1 and 3 inclusive, the supporting head 11 and the hanger member 10 are preferably of one solid unit, or may constitute one integral part. Furthermore, the clamp 13 is preferably permanently secured or fixed in position. 15

It should be understood that single strings or threads are used which are folded intermediate their ends over the bar 11, and their free ends are allowed to hang loose in the manner shown in Figure 2, thereby avoiding the necessity of 20 stitching or otherwise securing the strings, strands, threads or cords 12.

In Figures 4 to 7 inclusive, I have shown a modified type of the invention, wherein a hanger member 16 is illustrated, which hanger member 25 is provided with inturned ends 17 for supporting a cylindrical or tubular-like head 18, the ends 17 of the hanger member 16 fitting into the ends of the cylindrical or tubular-like head 18. This head 18 is provided with a plurality of perforations 19 throughout the length thereof and a perforated clamping member 20 is adapted to fit over the strands, threads, cords or the like 21, and thereby hold these strands 21 in firm position upon the head 18. These strands 21 are folded 30 intermediate their ends to overlie and fit around the head 18 in the manner shown in Figures 4 and 5, and in detail in Figure 6, the folded portions 22 of the strands 21 being adapted to fit between the perforated clamp 20 which is provided 35 with a plurality of perforations 23 and the perforated head 18, these perforations providing additional gripping means for firmly holding the threads against longitudinal slipping movement in the manner illustrated in detail in Figure 6. 45 The perforations 23 and the clamp 20 and the perforations 19 in the head 18, will provide means whereby the cords or strands will be forced into the perforations of the head and clamp when the two members are assembled, as indicated in 50 Figure 6, thereby providing efficient clamping means to hold the strands 21 against longitudinal slipping.

It will be noted from Figure 4 that the lower gripping edge of the clamp 20 is provided with a 55

plurality of notches 24, which notches provided a roughened or scallop-like lower gripping edge for the clamp.

From the foregoing description, it will be seen that a very simple and efficient comb cleaner has been provided and more particularly that a very efficient means is provided for holding the strands against slipping after they have once become secured to the head. These strands may be removed for replacement at any time it is desired to do so, simply by removing the clamp from the supporting head. It should be noted also that a very simple and efficient structure is provided which may be produced at a minimum cost.

It is preferable to provide the metal parts of suitable material which will not corrode or become affected when immersed in water so as to permit the device to be easily cleansed in a few moments in a cleansing material such as a soapy solution, without removing the strings from the head.

Having described the invention, what I claim is:

A comb cleaner of the class described comprising a supporting head, a hanger member carrying the head, cleaning strands folded over the head and having their free ends suspended therefrom, a clamping member fitting over the folded portions of the strands for firmly holding the strands upon the head against accidental displacement or slipping movement, said head having a plurality of perforations arranged throughout the length thereof, said clamp also having a plurality of perforations formed therein, the perforations providing means into which the strands are protruded when the clamp is clamped about the threads upon the head and providing a plurality of strand-receiving pockets to hold the strands against longitudinal slipping, said head comprising a tubular-like member, and the clamping member having a scallop-like gripping edge for firmly engaging the strands at the point where the strands leave the supporting head. 20

PATTY SHEPHERD KEYSER.
